SHEARING MACHINE

Application filed February 12, 1927. Serial No. 167,608.

This invention relates to shearing machines, and will be herein described as applying to the shearing of a sheet of strip material, although it has other applications.

Recent developments in the art of sheet rolling have led to the production of sheets of material sometimes one hundred fifty to two hundred feet long, which sheets are cut into lengths, doubled and rolled to final thickness.

In rolling such long sheets, so much time is consumed that the trailing end of the sheet is appreciably cooler at the time it reaches the rolls than was the leading end at the time it was in the rolls. As a result, the sheet is wedge shaped, the trailing end being thicker than the leading end. The long sheets or strips vary considerably in length, but are generally of substantially the same weight. It therefore becomes desirable to shear the sheet into sections which may be of varying length, but which are of substantially equal weight, and to reroll these sheared sections.

I provide a shear and feed means therefor. The feed means is controlled in such manner that the sheet may be cut into portions of desired weight. A gauge means is provided and the position of the first and last cuts on the sheet is determined by the operator. The driving connection for the feed means is effective for making the intermediate cuts at the right points. The sections into which the sheet is cut may be made of substantially uniform length as is desirable if the sheet is of uniform thickness from end to end. The sections cut from various long strips may be of varying length, depending on the relative length of the long strips themselves. I employ a variable ratio connection in the drive for the feed means. This variable ratio connection is adjusted by the operator when he determines the position of the first and last cuts.

In order to take care of the change in thickness of a sheet or strip which is to be sheared, I provide means for adjusting the variable ratio connection as the shearing operation progresses. In this manner, assuming that it is desired to cut sheets which are thicker at their trailing than at their leading end,

the apparatus will be effective for shearing successively shorter lengths from the strip. Means is provided for varying the amount of change so as to take care of different rates of change in thickness of the long strip or sheet.

In the accompanying drawings which illustrate the present preferred embodiment of my invention,

Figure 1 is a top plan view, partly broken away, showing the shearing mechanism and the means for supplying material thereto,

Figure 2 is a side elevation of the apparatus shown in Figure 1,

Figure 3 is a side elevation, to enlarged scale, of the shearing mechanism proper,

Figure 4 is a top plan view of the apparatus shown in Figure 3,

Figure 5 is a diagrammatic view showing a part of the driving connection for the feed means, and

Figure 6 is an end view of a part of the apparatus shown in Figures 3 and 4.

Figure 7 is a partial circuit diagram of the electrical apparatus embodied in the invention.

In the illustrated embodiment of the invention, there is shown a shear 2 actuated by eccentricities 3 on a shaft 4. The shaft is provided with a slidable clutch portion 5. A gear 6, having cooperating clutch teeth 7, rotates freely on the shaft 4. The gear 6 meshes with a pinion 8, which pinion is driven from a gear 9. The pinion 8 and gear 9 are connected to a shaft 10. The gear 9 meshes with a pinion 11 on a shaft 12. This shaft carries a fly wheel 13 and is driven through a silent chain connection 14 from a motor 15.

When the clutch member 5 is in engagement with the teeth 7 the shaft 4 is rotated and the shear 2 moves up and down at regular intervals.

The end of the shaft 4 remote from the gear 6 carries a disk 16 on which is mounted a crank pin 17 (Figure 5). A slider block 18, mounted on the pin 17, engages a slot 19 in a rocker arm 20 which is mounted on a shaft 21. The periphery of the rocker arm 20 is formed into a gear segment 22. The gear segment 22 engages a pinion 23 which is carried on a shaft 24. It will be seen that as

the shaft 4 rotates, the shaft 24 will be rotated first in one direction and then in the other direction. The direction of rotation of the shaft 4 is indicated by an arrow *r* in Figure 5, and the positions of the crank pin 17 for the ends of the stroke of the rocker arm 20 are indicated at *a* and *b*.

It will be observed that going in the direction of rotation, the distance from *b* to *a* is considerably greater than the distance from *a* to *b*. When the crank pin 17 is moving from *b* to *a*, the rocker arm 20 moves in the direction of the arrow *f*, and actuates connections with the shaft 24 for feeding material to the shear. The return stroke of the rocker arm 20 is made during the time that the crank pin 17 is moving from *a* to *b*, and the eccentric 3 are so timed with the crank pin that shearing is effected during this period.

It will be seen that considerably more than 180° of rotation of the shaft 4 is allowed for the feeding stroke. Shearing may be accomplished in a relatively short time, and with my construction the machine may be operated at a faster rate than can machines where only one half revolution of the shear actuating shaft is available for the feeding stroke.

The shaft 24 carries a two-toothed ratchet wheel 25 which is adapted to engage a pawl 26 secured to a gear 27. The gear 27 is freely rotatable on the shaft 24. The rocker arm 20 and pinion 23 are so proportioned that the shaft 24 makes a revolution in one direction or the other on each stroke of the rocker arm 20. When the rocker arm moves in the direction of the arrow *f*, the ratchet wheel 25 engages the pawl 26 and rotates the gear 27 in a counter-clockwise direction for one complete revolution. On the return stroke of the rocker arm, the gear 27 remains stationary and the ratchet wheel 25 rotates in a clockwise direction under the pawl 26. A step by step movement is thus imparted to the gear 27.

The gear 27 engages a gear 28 keyed to one shaft of a variable ratio device indicated generally by the reference character 29. The particular device shown is the well known Reeves variable speed coupling. This device consists of a pair of parallel shafts 30 and 31 having mounted thereon cone pulleys 32. The cone pulleys on each shaft have opposed faces and they may be moved toward or away from one another by arms 33 pivoted to the frame at 34. The position of the arms 33, and, therefore, the position of the cone pulleys 32 on the shafts 30 and 31, is determined by rotating a shaft 35. This shaft is connected to the arms 33 by links 36. A belt 37 extends around the shafts 30 and 31 and engages the faces of the cone pulleys. The belt is laterally stiffened by cross bars 38, and its edges engage the faces of the pulleys. By shifting the

pulleys on the shafts, the radial distance at which the belt engages the pulleys is changed, thus supplying a variable drive ratio between the shafts 30 and 31.

A gear 39 is keyed to the shaft 31 and meshes with a gear 40. The gear 40 is keyed to one of a number of feed rollers 41 by which the sheet or strip material is fed to the shear. The feed rollers are interconnected by pinions 42 (Figure 4) so that all of them may be driven. Only one pinion is shown, as it will be obvious that any desired drive may be employed. The pinions permit of each pair of rolls being spread apart, as hereinafter set forth, to facilitate entering of the sheet. Exit rolls 43 are also connected to the drive for the feed rolls 41. The rolls 43 insure that the sheared material will be removed from the apparatus as fast as shearing is accomplished. The scrap material falls to a conveyor belt 44, a guide or deflector 45 being employed to assist in the transfer. The delivery belt 44 is driven by a silent chain drive 46 connected through a shaft 47 and mitre gears 48 to the shaft 4.

The apparatus as so far described is effective for shearing material into lengths and provision is found in the variable ratio device for varying the length of the sheared portions. The apparatus for dividing sheets of variable length into a desired number of parts will now be described.

The sheets of material which it is desired to shear are indicated at *S* in Figure 2. They are carried on a bed 49, placed at the rear of the shearing machine. Figures 1, 2 and 3 illustrate the mechanism whereby the top sheet in the stack is carried forward to the shearing mechanism. A frame 50 is mounted on parallel arms 51 and 52. The arms are carried by shafts 53 and 54. A gear 55 is keyed to the shaft 53 and meshes with a pinion 56 driven by a motor 57. The motor is controlled by a switch lever 58.

A pair of feed rolls 59 is mounted on the frame 50. These rolls are ordinarily pressed together by springs 60 (Figure 3). They are driven by a motor 61 operating through a speed reducer 62 and a sprocket chain 63. A switch lever 64 is provided for controlling the motor 61.

A lifter arm 65, pivotally mounted on the frame 50 at 66, is provided for holding the feed rolls 59 apart when desired. A dog 67 is mounted on the frame 50. With the parts in the position shown in Figure 3, the dog engages a pin 68 on the arm 65 and holds the rolls apart.

When it is desired to feed a sheet, the motor 57 is actuated to swing the arms 51 and 52 in a clockwise direction, thus swinging the frame 50 over the stack of sheets and to the dotted line position of Figure 3. During this rearward travel the feed rolls are held apart and a workman lifts the front end of the top

sheet in the stack so that it passes between the feed rolls. When the frame 50 nears the end of its rearward travel, the dog 67 is engaged by a lug 67a which forces the dog out of engagement with the pin 68 and thus permits the feed rolls 59 to come together. The motor 61 is then operated until the leading end of the sheet lies alongside a gauge mark 69 on a guide 70. This gauge mark is removed from the point of shearing a distance equal to the total travel of the frame 50. The shearman so manipulates the switch 64 that the feed rolls 59 feed the leading end of the strip past the gauge mark 69. Figures 1 and 4 show in dotted lines the leading end of the sheet advanced to a point alongside the gauge mark. The mark indicates to the shearman the line of the first cut. It will be understood that at this time the frame 50 is still in its rearward position.

The next step in the feeding operation is to move the frame 50 from its rearward position to its forward position so as to move the leading end of the sheet into the shear. This is done by operating the motor 57 in a reverse direction, thus rotating the arms 51 and 52 counter clockwise. During the forward movement of the frame 50, the rolls 59 are not rotated and the sheet is pulled forward. The speed reducer 62 acts as a lock to prevent the rolls 59 from turning during the forward movement of the frame 50. During this feeding operation the several pairs of feed rolls 41 are held apart so as to permit entry of the leading end of the sheet.

The forward stroke of the frame 50 carries the leading end of the sheet under the shear 2 and since the gauge mark 69 is placed a distance away from the shear 2 corresponding to the amount of travel of the frame 50, the sheet will be positioned for a shear cut at the point indicated by the gauge mark 69.

During the forward stroke of the frame 50, the dog 67 "rides" on the pin 68. At the end of the stroke the arm is engaged by a stop 67b (Figure 3) which is effective for spreading the feed rolls so as to permit of the sheet passing freely through the shear. When the arm is engaged by the stop 67b the dog 67 drops into position and locks the feed rolls apart.

With the leading end of the sheet thus placed in position for the first cut, it is next necessary to gauge the trailing end of the sheet. This is done by a pointer 71 connected to a chain 72 running alongside the support 49. The chain runs over an idle sprocket 73 and an active sprocket 74. The active sprocket is connected through spur gearing 75 and mitre gears 76 to a shaft 77. The shaft 77 is driven by a motor 78 (Figure 1) through a speed reducer 79 and spur gearing 80. The motor 78 is controlled by a switch 81 having an operating rod 82 extending along the support 49 and provided with han-

dles 83 at different points along its length.

The shaft 77 is connected to one shaft of a change speed gear box 84. The gear box is provided with a driven shaft 85. The driven shaft 85 is connected through mitre gears 86 to a shaft 87. The shaft 87 carries a worm 88 meshing with a worm wheel 89. As the worm wheel rotates in one direction or the other, it swings an arm 90 connected through a link 91 to an arm 92. The arm 92 is keyed to the shaft 35 and is effective for changing the setting of the variable ratio connection 29. Therefore as the pointer 71 moves back and forth along the support 49 the variable ratio connection will be adjusted. By actuating the shifting handle 83 of the gear box 84, the amount of adjustment of the variable ratio connection for a given movement of the pointer 71 may be changed. In this manner, it is possible to provide for cutting a strip into the desired number of pieces having the proper length. The method of operating will be explained in detail later.

As above mentioned, the feed rolls are held apart while the leading end of the strip is being moved into the shear. The mechanism for holding the feed rolls 41 apart is shown in Figure 3. Each upper roll is normally pressed downwardly by springs 94. Bell crank arms 95, pivoted to the frame at 96, are effective for lifting the upper rolls when desired. The bell crank arms are connected by links 97. One of the bell cranks has a special arm 98 to which is connected a rod 99. The rod extends through a block 100 which is pivotally mounted on the arm 51. When the frame 50 is moved to its rearward position, the block 100 slides along the rod 99 until it engages a pair of nuts 101 which act as an adjustable stop. The stop 101 is so placed that it is engaged by the block 100 just before the frame 50 reaches the end of its rearward stroke. The last part of the rearward stroke is therefore effective for pulling on the rod 99 and spreading the feed rolls apart. A dog 102 locks the arm 98 against return movement so that the feed rolls are held apart on the forward stroke of the frame 50.

The shearing operation is carried out by releasing the dog 102 so as to bring the feed rolls 41 into engagement with the sheet and by shifting the clutch member 5 so as to throw the shear into operation. On each revolution of the shaft 4 the strip is sheared and is then fed forward in an amount depending upon the setting of the variable ratio connection. The last cut will be made at a point corresponding to the setting of the gauge mark 71. Means for actuating the dog 102 and the clutch member 105 is hereinafter described.

It is characteristic of the Reeves transmission that a material change in setting can only be accomplished when the transmission is running. I take care of this condition by

connecting the shaft 31 with the shaft 10 during the adjusting period. The shaft 31 carries a gear 103 meshing with a gear 104. The gear 104 rotates freely on the shaft 10 but is arranged to be driven by the shaft 10 when a clutch member 105 is in engagement with the gear. A lever 106 engages the clutch members 5 and 105 so that when the clutch member 5 engages the teeth 7 the clutch member 105 disengages the clutch teeth on the side of the gear 104 and vice versa. It follows that if the main drive is disconnected the shaft 31 of the variable ratio transmission will be driven. The feed rolls 41 and the gear 27 will also be driven through this connection, but this is immaterial.

In order that the various parts of the mechanism may be stopped in the proper position, I provide a semi-automatic mechanism for operating the clutch members 5. This is best shown in Figure 6. The clutch member 5 is provided with a face cam 107 having a high portion 108. The clutch member 5 is normally urged into engagement with the teeth 7 by a spring. A plunger 109 is normally urged to the position shown in Figure 6 by a spring 110, but it may be retracted by energizing a magnet 111. So long as the plunger 109 is retracted, the clutch member 5 will be in engagement with the teeth 7. If the plunger 109 is then raised to the position of Figure 6, it will engage the face cam 107, and as soon as it encounters the rise 108, will disengage the clutch member 5 and engage the clutch member 105, and will hold the parts in such position until the plunger is again withdrawn by energizing the solenoid 111. A magnet 112 (Figure 3) is arranged to trip the dog 102 when energized.

The magnets 111 and 112 are controlled by switch buttons 113 in each handle 83 and by a switch 114 (Figure 2). The switch 114 is effective for de-energizing the solenoids 111 and 112 when the frame 50 is moved to its rearward position. This is done by the shearmen who actuates the switch lever 58 as soon as the shearing of one strip has been completed. The rise 108 on the clutch member 5 is so positioned that the shaft 4 will be disconnected with the shear 2 in its upper position and with the rocker arm 20 ready to make a complete feeding stroke.

The switch buttons 113 are effective for energizing the magnets 111 and 112 and thus setting the shear into operation. They will normally be actuated by the workman who sets the gauge point 71. He can thus set the shear into operation as soon as he has determined the position of the last cut.

The apparatus as so far described is effective for cutting a strip into sheets of equal length. The means for adjusting the variable ratio connection as the shearing operation progresses will now be described. It is this apparatus which is effective for pro-

gressively varying the length of the sheared sheets, thus compensating for increase in thickness.

The shaft 87 is connected through gears 87g to a ratchet wheel 115 having a pawl 116. The pawl is mounted on a rocker arm 117 connected through a link 118 to a stud 119. The stud 119 is adjustable to different positions in a diametral slot 120 formed in a disk 121 secured to the end of the shaft 21. Each time the rocker arm 20 makes a stroke, it effects a stroke of the rocker arm 117 and thus, if the pawl 116 is left in engagement with the ratchet wheel 115, causes a partial rotation of the shaft 87 and a corresponding adjustment of the variable ratio connection. The amount of this supplemental adjustment may be varied by changing the setting of the stud 119 in the slot 120.

When it is desired to cut a strip into progressively varying lengths the pawl 116 is left in engagement with the teeth of the ratchet 115. Therefore, every time the rocker arm 20 makes a stroke the variable ratio connection is adjusted in a certain amount depending upon the fitting of the stud 119 into the slot 120. Since the feed rolls are actuated through the variable ratio connection it follows that the amount the strip is fed forward upon successive actuations of the feed roll 95 will vary in an amount depending upon the amount of adjustment of the variable ratio connection.

Having completed the description of the structure of the invention, I shall now outline briefly the method of operation. In the following explanation, it will be assumed that a strip has just passed through the shears and that the electro-magnets 111 and 112 are energized so that the clutch 7 is engaged to drive the feed rolls 41 through the variable speed drive 29 and to permit the feed rolls 41 to engage their co-operating rolls under the influence of the springs 94. The motor 15 is continuously energized and furnishes the driving force for the machine.

In order to start another strip through the machine, the switch 58 is closed to drive the motor 57 in such direction as to rotate the arms 51 and 52 in a clockwise direction. The rolls 59 are separated because of the previous engagement of the stop 67 with the arm 65, and they are maintained in this position by engagement of the dog 67 with the pin 68. As the arms 51 and 52 approach their rear-most position, the switch 14 is operated to de-energize the electromagnets 111 and 112. The deenergization of the electromagnet 111 disengages the clutch 5 and causes the clutch 105 to become engaged. The deenergization of the electromagnet 112 permits the detent 102 to lock the rod 99 in its retracted position when the lock 100 has engaged the lock nuts 101, as a result of the movement of the arms 51 and 52. The disengagement of the clutch 105

5 causes the shaft 4 to come to a standstill, so that the shear 2 is no longer reciprocated. The variable speed drive 29 would likewise come to a stop, except for the engagement of 5 the clutch 105 which drives it directly from the shaft 10.

The strip to be sheared is placed between the rolls 59 before the arms 51 and 52 reach the rear limit of their motion, at which point 10 the stop 67a trips the dog 67 to permit the rolls 59 to engage the strip. The switch 64 is operated to start the motor 61, which drives these rolls. The strip is advanced until its head end is in line with the gauge mark 69 on 15 the guide 70. The switch 64 is then operated to start the motor 61 and the switch 68 is operated to reverse the motor 57 to restore the arms 51 and 52 to their normal position. The feed rolls 41 are maintained separated by the 20 detent 102 which engages the drive line 9, so that the head end of the strip is placed between the feed rolls, although the latter do not engage it tightly.

The strip is now ready for the commencement 25 of the shearing operation. Since its head end is between the shear blades in position for the first cut, it remains only to adjust the variable speed drive so that the length of the fixed number of sheets cut from 30 the strip will be properly adjusted to ensure that the entire strip is sheared into the fixed number of sheets.

In order to adjust the variable speed connection 49, in accordance with the length of 35 the strip, the motor 78 is operated by closing the switch 81 to shift the index 71 until it lies adjacent the end of the strip. Simultaneously, the variable speed drive is adjusted so that the movement of the strip through the 40 shear between successive shearing operations will be such as to divide the entire strip into a fixed number of sheets. The variable speed drive 29 is maintained in rotation by engagement of the clutch 105. When this adjustment 45 has been completed, the shear is ready to be started. The change gear box 84 is provided to permit a variation in the change of the setting of the device 29 by a given movement of the pointer 71 and the change gear 50 box will be set so as to cause the proper change in the setting of the variable speed drive 29 for a given movement of the pointer, to make allowance for the variations in strip lengths.

To start the shear, the operator closes one 55 of the switches 113, which energizes the electromagnets 111 and 112. The energization of the electromagnet 111 causes the clutch 5 to become engaged so that the feed rolls 41 may be driven through the variable speed connection 29 at the proper speed. The energization of the electromagnet 112 causes the withdrawal of the detent 102 to permit the feed rolls 41 to grasp the strip and advance it 60 through the shear.

In case the rear ends of the strips are thinner than the head ends, it will be desirable to take longer and longer cuts from the strip as it proceeds through the shear. If the strips are thicker at the tail end, the sheets should 70 be cut shorter and shorter as the strip is sheared. This variation in the length of successive sheets is accomplished by the automatic means for shifting the variable speed device 29 after the shearing mechanism has 75 commenced operation. As the rocker arm 20 oscillates, the lever 117 causes a step by step movement of the pawl 115, which effects a progressive adjustment of the variable speed drive 29. It will thus be apparent that the 80 latter is adjusted twice in the shearing of a strip. The first adjustment is that resulting from the movement of the index 71 to the end of the strip. This adjustment accounts for variations in the length of the strips. 85 The second adjustment is that effected by the ratchet and pawl, and compensates for differences in thickness of the two ends of the strip. If the strip is of uniform thickness, the pawl 116 may be disengaged from the 90 ratchet 115, so that all the sheets are sheared to the same length.

When the strip has passed through the shear and the last cut has been taken at the point at which the index 71 was set, the conditions are the same as those assumed at the beginning of this explanation, a complete cycle of operations having been described. This cycle is completed for each strip 95 sheared.

The adjustment of the automatic control of the variable speed device 29 is effected by shifting the stud 119 in the slot 120 of the disc 121. The setting of the stud 119 need be changed only when the rate of change 100 of thickness of strips varies. Since all the strips in the given batch will have substantially the same rate of change of thickness from end to end, it will not be necessary to set the stud 119 very often.

It will be apparent from the foregoing description and explanation that I have provided a shearing machine which is adapted to shear strip material into a predetermined 105 number of sheets having variable lengths controlled in accordance with the thickness of the strip. Variations in the lengths of the strips are accounted for by adjusting the speed of the feeding mechanism, so that the entire strip is sheared into the required number of sheets.

I have illustrated and described a preferred embodiment of my invention, but it will be understood that the invention may be otherwise embodied within the scope of the following claims:

I claim:

1. In a shearing machine, shear means, feed means, drive means for the feed means, a variable ratio connection between the feed means and the drive means, adjusting means 115

for the variable ratio connection, and means for driving the variable ratio connection independently of said drive units while the adjustment is being made.

5. 2. In a shearing machine, shear means, feed means, drive means for actuating the shear means and the feed means, a variable ratio connection in the drive for the feed means, adjusting means therefor, and means for driving the variable ratio connection independent of the shear drive means so as to permit adjustment of the variable ratio connection.

10. 3. In a shearing machine, shear means, feed means, a drive means for the feed means, a variable ratio connection between the drive means and the feed means, clutch means between the drive means and the variable ratio connection, and means for driving the variable ratio connection when the clutch means is disengaged.

15. 4. In a shearing machine, shear means, feed means, drive means for the feed means including a reciprocable member and a variable ratio means, and a connection between the reciprocable member and the variable ratio means effective for adjusting the variable ratio means.

20. 5. In a shearing machine, shear means, feed means, drive means for the feed means including a reciprocable member and a variable ratio means, a connection between the reciprocable member and the variable ratio means, and means for varying the amount 35 of adjustment effected by a stroke of the reciprocable member.

25. 6. In a shearing machine, shear means, feed means, a driving connection for the feed means including a variable ratio means, means for automatically adjusting the variable ratio means during the shearing operation, and hand controlled means for adjusting the variable ratio means.

30. 7. In a shearing machine, shear means, feed means therefor, a driving connection for the feed means, gauge means adjustable to different positions, a connection between the gauge means and the driving connection effective for modifying the action of the feed means so as to vary the amount of material fed to the shear means upon different actuations of the feed means.

35. 8. In a shearing machine, shear means, feed means, a driving connection therefor, a pair of relatively movable gauge points, means for moving a piece of material into position to be gauged by such points, a connection between one of the gauge points and the driving connection effective for varying the amount of material fed to the shear means upon actuation of the feed means, shear stopping means controlled by the means for moving a piece of material into position to be gauged, and shear starting means alongside the gauge means.

9. 9. In a shearing machine, drive means, shear means, feed means for supplying material to the shear means, connections effective for operating the shear means and the feed means from the drive means, a variable ratio means in the connection to the feed means and means operable when the connection is broken for driving the variable ratio means.

10. 10. In a shearing machine, drive means, shear means, feed means for supplying material to the shear means, a shaft for driving the shear means and the feed means, a clutch for connecting the shaft to the drive means, a variable ratio means interposed between the drive means and the feed means, an auxiliary shaft for driving the variable ratio means, a clutch for the auxiliary shaft, and a connection between the clutches so arranged that when one is thrown into operation the other is thrown out of operation.

11. 11. In a shearing machine, drive means, shear means, feed means for supplying material to the shear means, a shaft for driving the shear means and the feed means, a clutch for connecting the shaft to the drive means, a variable ratio means interposed between the drive means and the feed means, an auxiliary shaft for driving the variable ratio means, a clutch for the auxiliary shaft, a connection between the clutches so arranged that when one is thrown into operation the other is thrown out of operation, a support for the material to be supplied to the shear, and control means adjacent the support for actuating the clutches.

12. 12. In combination with a shear having feed rolls, a material engaging device movable toward and away from the shear and arranged to bring material into position to be engaged by the feed rolls, and means actuated by the movement of the material engaging device for operating the feed rolls for the reception of said material.

13. 13. In combination with a shear having feed rolls, a material engaging device movable toward and away from the shear, means actuated by the movement of the material engaging device for separating the feed rolls, control means for starting the shearing operation, and means operable substantially simultaneously therewith for causing the feed rolls to come together.

14. 14. In combination with a shear having feed means, a control means for throwing the feed means out of operation, and a device movable toward and away from the shear and effective for carrying material to the shear and its feed means, said device being effective for actuating the control means.

15. 15. In combination with a shear, a frame movable toward and away from the shear, feed rolls on the frame, and means for driving the rolls in a direction to feed material to the shear, the rolls being adapted to be

maintained non-rotatable and effective for gripping the material when the frame is moved toward the shear.

16. In a shearing machine, shear means, feed means and means actuated upon operation of the machine for automatically modifying the action of the feed means so as to vary the distance the material is fed upon different actuations of the feed means.

17. In a shearing machine, shear means, intermittently operated feed means and means actuated upon operation of the machine for automatically modifying the action of the feed means so as to vary the distance the material is fed upon different actuations of the feed means.

18. In a shearing machine, shear means, feed means, drive means effective for intermittently actuating the feed means, said drive means including a variable connection and means actuated automatically by movement of the machine for adjusting the variable ratio connection so as to cause a difference in the amount of material fed upon different actuations of the feed means.

In testimony whereof I have hereunto set my hand.

GEORGE W. RUSSELL.
